CLAIM

The ornamental design for a tool for removing wires and bolts from ceilings, as shown and described.

DESCRIPTION

FIG. 1 is a front perspective view of a tool for removing wires and bolts from ceilings showing my new design; FIG. 2 is a front elevational view thereof;

FIG. 3 is a bottom plan view thereof;

FIG. 4 is a right side elevational view thereof;

FIG. 5 is a rear elevational view thereof;

FIG. 6 is a top plan view thereof;

FIG. 7 is a left side elevational view thereof;

FIG. 8 is a front elevational view of a second modified embodiment;

FIG. 9 is a rear elevational view of FIG. 8;

FIG. 10 is a left side elevational view of FIG. 8; and,

FIG. 11 is a right side elevational view of FIG. 8.

The tool is shown fragmentarily for ease of illustration.
